UNITED STATES PATENT OFFICE.

ARTHUR M. BURNHAM, OF GARDINER, MAINE.

OVEN.

1,193,869.

Specification of Letters Patent. Patented Aug. 8, 1916.

Application filed September 19, 1914. Serial No. 862,512.

To all whom it may concern:

Be it known that I, ARTHUR M. BURNHAM, a citizen of the United States, residing at Gardiner, county of Kennebec, State of 5 Maine, have invented an Improvement in Ovens, of which the following description, in connection with the accompanying drawing, is a specification, like characters on the drawing representing like parts.

10 This invention relates to cooking ovens of that type which are heated by gas, electricity, or some similar heating medium, and the object of the invention is to provide an improved oven of this type having means for 15 automatically controlling the heating medium so as to maintain any desired temperature in the oven chamber.

I propose to provide a plurality of heating elements, and the controlling device is 20 of such a nature that as the temperature in the oven increases beyond a predetermined point the heating elements will be successively rendered inoperative, while when the temperature begins to drop from its maximum point, the heating elements will be rendered successively operative again, this 25 action being automatic so that the temperature can be maintained at any desired point. I have also provided means whereby when 30 all of the heating elements have been rendered inoperative, the air inlet opening to the oven chamber will be closed so as to prevent the rapid escape of the heat therefrom by convection. Further I have provided a 35 thermostatic device for controlling the valves which is constructed to eliminate all lost motion and which, therefore, will be extremely sensitive and accurate.

These and other features and objects of 40 my invention will be more fully hereinafter described and the novel features of the invention will be pointed out in the appended claims.

In order to give a proper understanding 45 of my invention, I have illustrated in the drawings a selected embodiment thereof in which—

Figure 1 is a front view of an oven made in accordance with my invention; Fig. 2 is 50 a partial side view of the oven showing one form of adjusting device for the thermostatic rod; Fig. 3 is a section on the line $x-x$, Fig. 2; Fig. 3^a is a reduced horizontal

section through the oven on the line $k-k$, Fig. 1, showing another arrangement of the 55 thermostatic rod. Fig. 4 is a plan view of the fuel supply valves and the controlling device therefor; Fig. 5 is a vertical section view through the oven; Fig. 6 is a detail showing the manner of operating the valves 60 for the air inlet opening; Fig. 7 is an enlarged section on the line $y-y$, Fig. 8; Fig. 8 is an end view of the valve-controlling mechanism showing the means for winding 65 the valve-actuating springs; Fig. 9 is a plan view of the bottom of the burner chamber showing the air inlet openings; Fig. 10 is a vertical sectional view through the burners and bottom of the burner chamber showing the manner of controlling the valves for 70 the air inlet openings; Fig. 11 is an enlarged sectional view through one of the fuel supply valves on the line $a-a$, Fig. 4; Fig. 12 is a section on substantially the line $b-b$, Fig. 75 11; Fig. 13 is a section on the line $c-c$, Fig. 11; Fig. 14 is a detail of the escapement device of the valve-controlling mechanism; Fig. 15 is a fragmentary sectional view showing the manner of adjusting the oven bottom; Figs. 16 and 17 show other arrangements of the thermostatic rod which embody 80 my invention, and Fig. 18 is a fragmentary view showing the operating means for controlling the air inlet valve 62.

I have herein shown my invention as it 85 might be embodied in an oven which has a superposed broiler attachment, but this arrangement is not essential.

The oven herein shown is constructed with a base portion 1, preferably of cast iron, 90 with a solid front 2 also preferably of cast iron and which is herein shown as bolted to lugs 7 rising from the base, and with the angle-iron posts 6 at the rear corners of the oven which are also secured to the base 1 and 95 to which the sides, back and top of the oven are secured.

My improved oven is constructed with heat-insulated walls having provision for storing up heat therein. In the illustrated 100 embodiment of the invention the side and back walls of the oven are provided with a dead air space 3 and with a lining 4 of some heat-conserving material which will readily absorb heat but will retain the heat thus absorbed. Soapstone is a good material for 105

this purpose, but any heat-conserving material may be employed. The dead air space 3 is formed between two sheet-metal walls 5 that are secured to and retained in position 5 by the legs of said angle iron posts 6 at the rear corners of the oven and by the flanges 8 formed on each side of the front 2 of the oven, as seen in Fig. 3. The dead air space 3 constitutes a heat insulation which prevents 10 the escape of heat by radiation and the lining 4 of heat-conserving material absorbs and retains the heat in the oven and prevents the oven from cooling rapidly when the heating elements are rendered inoperative. The front 2 of the oven is provided with a door opening which is closed by the usual door 9.

While so far as many features of this invention are concerned, it would be possible 20 to use any suitable heating element, whether in the nature of a gas burner or electrical heating element, yet I have herein chosen to illustrate the invention as embodied in a gas-heated oven.

25 The oven is herein provided with an oven bottom 10 which divides the oven into a heating or cooking chamber 11 and into a burner chamber 12, the latter having some suitable burner 13 therein. The oven bottom 10 will preferably be made of some heat-conserving material, such, for instance, as soapstone, and is of such dimensions as to provide a passageway 14 forming a communication between the cooking chamber 11 and the burner chamber 12. The oven is also provided with a discharge passage for the escape of the products of combustion, such passage being shown at 15 and extending along over the top of the oven and down 40 the back side of the oven to the outlet port 16 which communicates with a flue 17 at the back of the oven. The space or passage 15 will preferably extend the full width of the oven and communicates with the oven chamber 12 at the top thereof near the front, as shown at 18. With this arrangement the heated air delivered from the heating element 13 will pass through the space 14 into the heating chamber 11 and will then pass 45 through the opening 18 into the discharge passage 15 and thence to the flue 17. The passage of the hot gases through the passage 15 keeps the top and back side of the oven heated and thus increases the efficiency of the oven. At the outer side of the passage 15 the oven will preferably be provided with heat-insulating material 19 which will prevent the loss of heat by radiation.

50 The bottom 20 of the burner chamber 12 is provided with one or more air inlet openings 21 through which air is supplied to support combustion.

One feature of my invention relates to a 55 novel thermostatic device for controlling the operation of the heating elements in the

burner chamber 12, whether these heating elements be in the nature of gas burners or be in the nature of electric heaters. This thermostatic device is in the nature of the usual thermostatic rod or bar which extends 70 transversely through the oven and which operates by its expansion and contraction to render the heating elements operative or inoperative. In my improved device, however, this thermostatic bar is so mounted and 75 constructed that all lost motion is eliminated and the apparatus is, therefore, made extremely effective and sensitive. Furthermore, the manner of mounting the thermostatic rod is very simple and inexpensive. 80 As shown in Fig. 3, one end of the thermostatic rod 22 extends through the flange 8 of the front 2 and has screw-threaded thereon an adjusting nut 23 which rests against the outside of the flange 8. This adjusting 85 nut is shown as provided with gear teeth 24 which mesh with a gear 25 mounted on the stud 26 and having associated therewith an indicator drum 27 that is visible through an opening 28 in the front 2. This indicator 90 drum 27 is graduated to indicate temperatures. The other end of the thermostatic rod 22 projects through the opposite side of the oven chamber 11 and is pivotally connected to a lever 29 which is pivoted to the 95 outside of the oven at 30. This lever is connected at its lower end, as at 31, to a controlling bar 32 by which the operation of the heating elements are directly controlled. Said bar 32 has a spring 33 connected thereto which tends normally to move the bar to the right Figs. 1 and 4. This spring thus keeps the nut 23 firmly against the flange 8 of the front 2 and takes up all lost motion in the connections. As the thermostatic rod 100 22 expands or contracts the bar 32 will have a movement which, however, is very much greater than the amount of expansion or contraction of the rod 22 owing to the relative lengths of the lever arms of the lever 29. During such movement of the bar 32 the spring 33 yields but always keeps the 105 connections taut.

In Figs. 3^a, 16 and 17 I have shown other arrangements of the thermostatic member 11^a which embody my invention. In Fig. 3^a a construction is illustrated by which the expansion of the thermostatic rod is considerably multiplied. As illustrated in said figure the thermostatic rod 22 is pivoted at one end at 241 to a member 240 that extends along one side of the oven exterior thereto and at the other end said thermostatic rod 22 is pivotally connected to another member 243 that extends along the other side of the 120 oven exterior thereto. The member 240 has extending laterally from its front end a screw-threaded projection 275 which extends through a flange 276 formed on the oven front 2 and to which the adjusting nut 130

23 is screw-threaded. The rear end of the member 240 is connected to the rear end of the member 243 by a connection 242 which is sustained in suitable guides 244 carried by the oven and the front end of the member 243 is pivotally connected to the lever 29 which in turn is connected at its lower end to the bar 32. In this embodiment of the invention the thermostatic rod 22 is located near the rear of the oven and the construction is such that any expansion or contraction of the rod 22 is greatly multiplied in the movement of the bar 32. Moreover the spring 33 will operate to maintain all of the connections and joints tight and will prevent any lost motion. In Fig. 16 I have illustrated a different arrangement for multiplying the expansive movement of the thermostatic member. In this embodiment of the invention the thermostatic member comprises three elements, 220, 221 and 222 which are connected together by a system of levers. The member 220 projects through the side of the oven and has the adjusting nut 23 screwed thereto. Said member is connected to one end of a lever 224 pivoted at 225, the other end of said lever being connected to one end of the member 221. This member 221 is also connected to one end of a lever 223 at the opposite side of the oven which lever is pivoted at 226 and is also pivotally connected to the other thermostatic member 222, the latter extending through the side of the oven and being pivoted to the upper end of the lever 29. The levers 223 and 224 are illustrated as pivotally connected to the flanges 8 of the oven front 2. With this arrangement all three of the thermostatic members 220, 221 and 222 will expand and contract and the total movement given to the lever 29 will be the sum of the expansive movement of the three members 220, 221 and 222.

In the above described embodiment of the invention both the lever 29 and the adjusting nut 23 are carried by and have bearing on the oven front 2. Under some conditions of use, the oven front may become heated to such an extent that with this arrangement the expansion thereof will affect the accuracy of the operation of the device. If these conditions arise I may provide means for supporting the lever 29 and the thermostatic rod independently of the oven front as shown in Fig. 17 wherein a supporting frame 151 is employed which embraces the oven front and to which the lever 29 is pivotally mounted and against which the adjusting nut 230 has bearing. This supporting frame is shown as having a U-shape, the lever 29 being pivotally connected to one arm thereof and the adjusting nut 230 which has screw-threaded engagement with the thermostatic rod 22 bearing against the other arm thereof. This supporting frame

151 may be secured to the oven front 2 but suitably insulated therefrom so that it will not become heated while the oven is in use. With such an arrangement any expansion or contraction of the oven front 2 will not interfere at all or affect the accuracy of the thermostatic device. 70

So far as the operation of the thermostat as thus far described is concerned the bar 32 might control electric switches for an electric heating element or valves for a gas burner. It is the latter construction which I have chosen herein to illustrate and which will now be described. 75

In the preferred embodiment of my invention I employ a plurality of burners with a valve for each burner, and provide means whereby as the thermostatic rod 22 expands and the controlling bar 32 has its corresponding movement, the valves of the burners will be closed successively, while when the thermostatic rod 22 contracts the corresponding movement of the bar 32 will operate to cause the valves to be opened successively. While any number of burners and their valves may be used, I have herein illustrated two burners and two valves therefor. The two burners are shown at 34 and 35, respectively, and they are supplied with gas from a main supply pipe 36 through two branch pipes 37 and 38, each pipe having a valve (39 and 390) therein, the operation of which is controlled by the bar 32. The construction of the valve which I prefer to use is best seen in Figs. 11, 12 and 13 and it comprises a stationary valve member 40 provided with two separated chambers 41 and 42, one constituting an inlet chamber and the other an outlet chamber, said chambers being connected with the branch pipes (37 or 38). 95 100 105 This valve member 40 is also provided with a valve seat face 43 having a plurality of ports therethrough which lead into the chambers 41, 42, there being three ports leading into each chamber, the ports leading into the inlet chamber 42 being designated 44 and those leading into the outlet chamber being designated 45. The valve also is provided with a movable valve member 46 formed with a chamber 47 and with a valve seat face 48 that fits the valve seat face 43, the latter having a plurality of ports 49 therein adapted to register with the ports 44, 45 when the valve member 46 is in proper position. The valve member 46 is 110 115 120 125 rotatively mounted on the valve member 40, this being herein accomplished by providing the movable valve member 46 with a stem 50 which extends through the valve member 40 and is mounted to turn therein. The valve faces 48 and 43 are yieldingly held in engagement by means of a spring 52 which encircles the stem 50 and engages the valve member 40 at one end and at the other end engages a collar 51 on the stem 50. 130

There will preferably be six ports 49 in the valve member 46 so arranged that when the valve member is in the position shown in Fig. 12 said ports 49 register with both the ports 44 and 45, and when this condition exists there will be a free passage of gas from the inlet chamber 42 through the ports 45 into the chamber 47 and from the chamber 47 through the ports 45 into the outlet chamber 10 41, and thence on to the pipe leading to the burner. When the valve member 46 is turned forward slightly the ports are carried out of register with each other and the gas is, therefore, shut off.

15 I have provided herein automatically-operative means preferably in the form of a valve-actuating spring which tends normally to rotate the valve member 46, and the operation of this spring is controlled by the bar 32. Inasmuch as the two valve-operating mechanisms are similar a description of one will suffice for both. Under normal conditions the valve will be opened and the valve-actuating spring will be held from operation 20 by the bar 32 until the temperature in the oven reaches a predetermined point, at which time the bar 32 has been moved into a position to release the spring and allow it to act to close the valve. There 25 is a spring for actuating each valve, said springs being shown at 53. These springs are herein illustrated as coiled springs which are mounted on a rod or support 54, one end of each rod being journaled 30 in a bearing 55 rising from the base 1, and the other end being connected to the valve member 46. One end of the spring 53 is connected to the rod 54 so that the tendency of the spring to unwind tends to turn the 35 rod 54 and thus to turn the valve member 46. Means are provided for winding up the spring from the other end, as will be presently described. Each rod 54 has fast thereto a toothed disk 56, the successive teeth 57 40 of which are out of line with each other. These teeth coöperate with the bar 32 to control the operation of the valve. The bar 32 is provided with a notch 58 of a size to admit the passage therethrough of the teeth 57, and under normal conditions this notch 45 is so positioned as to be out of line with the teeth so that one of the teeth 57 will engage the bar 32 and thus hold the spring 53 from unwinding.

55 When the bar 32 moves into a position to bring the notch 58 opposite the tooth which rests on the bar, then the expansive movement of the spring will carry said tooth through the notch, thus allowing the valve to 60 be given a partial turning movement. This turning movement is arrested, however, by the next tooth 57 which being out of line with the first-named tooth will be out of line with the notch and will, therefore, be 65 brought up against the bar 32. The teeth

57 are spaced apart an angular distance equal to half the angular distance between the ports in the valve member 40, so that, assuming that the valve is open, the first forward movement of the disk and valve member 46 will close the valve, while the next forward movement will bring the ports into alinement again, thus opening the valve. With this construction, therefore, the valve will be alternately opened and closed as the valve member rotates. This valve construction is one in which the valve member 46 is designed to rotate continuously in the same direction and during such rotation the valve will be alternately opened and closed. 80 The construction of the parts is such that when the oven is not heated the notch 58 will be at the left-hand side of the disk 56. As the oven becomes heated and the thermostatic rod expands the bar 32 will move to the right 85 Fig. 4, and when the notch 58 comes in alinement with the tooth which engages the bar, then the valve member will move forward one step until the next tooth brings up 90 against the bar. This step forward will close the valve and when the oven cools and the thermostatic rod contracts the movement of the bar 32 in the opposite direction will again bring the notch into alinement with the tooth which rests thereagainst, thus allowing the valve to have another step forward thereby to open it again. This disk 56 and the bar 32 thus form a sort of escape- 95 ment device which operates to effect an alternate opening and closing of the valve as 100 the thermostatic bar expands or contracts.

As stated above, the bar 32 is designed to control both valves 39 and 390 and I will preferably so arrange the parts that these valves will be operated successively rather 105 than simultaneously. This is accomplished by so arranging the valves 39 and 390 that the disks 56 of both valves will engage the bar 32 and so arranging the notches 58 for the two disks that one notch will come into 110 register with its disk 56 before the other notch does. As shown in Fig. 4, the construction is such that the valve 390 will first be operated, and if the thermostatic rod continues to expand after this valve is closed 115 then the other valve 39 will be closed, but if when the valve 390 has been closed the temperature in the oven remains at substantially the same point, then the valve 39 will remain open. I propose to make the two 120 burners 34 and 35 of different sizes. The burner which is supplied by the valve 39 will preferably be somewhat smaller than the other burner. The advantage of this construction is that when the oven reaches 125 a predetermined temperature and the valve 390 becomes closed, the smaller burner supplied from the valve 39 will presumably furnish just about enough heat to hold the temperature in the oven. If, however, the 130

heat furnished from the burner supplied by the valve 39 is sufficient to increase rather than to just maintain the temperature in the oven chamber, then the valve 39 will become closed. If both valves have been closed, then when the temperature in the oven decreases the valves will be successively opened, the valve 39 being opened first. The temperature at which the valve 390 will be closed 5 can be determined by adjusting the indicator, for it will be readily observed that since the nut 23 bears against the side of the oven any turning movement thereof will shift the thermostatic rod 22 longitudinally and thus 10 shift the position of the bar 32 relative to the disks 56. The numbers on the indicating disk 27 will be so arranged that the number which is visible through the sight opening 28 will indicate the temperature at which the 15 valve 390 will be closed. 20

In order to prevent any binding of the parts I propose to provide a flexible coupling between each rod 54 and the corresponding valve member 46. As herein 25 shown, each valve member is provided with pins 60 extending therefrom which loosely engage apertures or notches formed in the head 61 mounted on the end of the shaft 54 so that turning movement of the shaft will 30 be communicated to the valve member, but the parts will not bind even though said valve member and shaft 54 are not axially in alinement.

I have also provided herein means for 35 controlling the passage of air through the inlet openings 21 so that when the burners are in operation a sufficient amount of air will be delivered through said openings to support combustion while when the burners 40 are shut off the openings 21 are substantially closed thereby preventing the passage of a current of air through the oven which will cool the latter. In the preferred embodiment of my invention I provide a construction 45 by which, when the valve 390 is closed the air inlet openings 21 will be partially closed and when the valve 39 is closed said air inlet openings will be completely closed.

As shown in Fig. 10 there are two air in- 50 let ports or openings 21 and a valve 62 is provided for closing each port. Said valves are carried by arms that are pivoted to the bottom 20 at 63 and the arms extend beyond the pivot points 63 as shown at 64, said 55 extensions 64 overlapping each other and one extension carrying a rod or pin that operates in a slot in the other extension. The valves are thus connected so that they move in unison. The rod or pin 65 is connected 60 by a ring 66 with an arm 67 fast on a rock shaft 68 that is mounted to turn in suitable bearings and this rock shaft has fast thereon two arms 301 and 302 which coöperate with two cam members 69 and 690, respect- 65 tively, by which the operation of the valves

62 are controlled. Cam member 69 is fast on the shaft 54 controlling the valve 39 and the cam member 690 is fast on the shaft 54 controlling the valve 390 and the construction is such that when the valve 390 is closed 70 the cam member 690 will allow the valves 62 to become partially closed while when the valve 39 is closed the cam member 69 will allow the valves 62 to become completely closed. In the illustrated embodiment of 75 the invention the cam members 69 and 690 operate to hold the valves open and the closing movement of the valves is secured by some automatically operative means such as the spring 72, which is connected to the arm 80 85 67. Each cam member 69 and 690 is provided with a series of rises 70 and depressions 71, there being the same number of rises and depressions on each member as there are teeth on the disk 56 for the two valves. The rises 70 on the cam member 690 are higher than those on the cam 69 and the depressions 71 on the cam member 690 are deeper than those on the cam member 69. When both valves are open the cam members 90 95 69 and 690 are in the relative positions shown in Fig. 18 and one of the rises or projections 70 on the cam 690 will be in engagement with the arm 302, thus holding said arm depressed against the action of the spring 72 and holding the valves 62 open. The relative dimensions of the rises 70 on the two cam members 690 and 69 are such that when the cam member 690 is in the 100 position shown in Fig. 18, the arm 301 will be separated somewhat from the adjacent rises 70 on the cam member 69. Whenever the valve 390 is closed as above described, the cam member 690 will be given one forward step thereby to carry the rise 70 out of engagement with the arm 302 and allowing said arm to move upwardly through the action of the spring 72. Such upward movement of the arm is however arrested by the arm 301 coming into engagement with 105 the cam member 69 and the parts are held in this intermediate position so long as the valve 39 remains open. This partial movement of the rock shaft 68 and arm 67 is permitted when the cam member 690 is moved 110 forward, one step being sufficient to partially close the valve 62 thereby reducing the amount of air which can pass through the air inlet openings. When the valve 39 is closed and the cam member 69 moved forward one step, then the spring 72 acts to 115 completely close the valves 62 as will be obvious. The parts are so arranged that when the valves 62 are partially closed as occurs after the valve 390 has been closed, the amount of air which will be admitted through the inlet openings 21 is just sufficient to support combustion of the burner still remaining in operation. By this arrangement, whereby the valves 62 are closed 120 125 130

progressively as the burners are shut off, I prevent the possibility when only one burner is lighted of a current of air of sufficient volume passing through the oven to cool the latter and I provide means whereby the amount of air delivered to the burners is at all times just sufficient to properly maintain the burners in operation.

The advantage of this construction is that sufficient air will be supplied to the burners to support combustion so long as either are in operation, but whenever both burners are shut off, then the passage through the oven chamber 11 is closed so as to prevent the escape of heat by convection.

I have also provided means for automatically winding the springs 53 which means are herein shown as operated by the oven door 9, the construction being such that the opening and closing movement of the oven door 9 acts to wind the springs. The construction is also of such a nature that the opening movement of the door will wind one spring while the closing movement will wind the other, but this particular arrangement is not essential to the invention. Each spring 53 is anchored at one end to a disk 73 loosely mounted on the shaft 54 and having frictional engagement with a gear member 74 also loosely mounted on the shaft. These two members 73 and 74 are held in frictional engagement by a spring washer 75, thus making a frictional clutch between them. The gear 74 meshes with a rack 76 which is slidably mounted in suitable guides and is connected by means of a link 77 with a crank arm 78 formed on the pivot shaft 79 of the oven door 9. The member 73 is in the form of a ratchet, it having ratchet teeth thereon which are engaged by a pawl 80 to prevent rotation thereof in one direction. With this construction it will be seen that the movement of the rack bar 76 will rotate the gear 74, and when the gear 74 rotates in one direction the friction member 73 will be driven forwardly by it thereby winding up the spring 53, while when the gear member 74 rotates in the other direction, due to the reverse movement of the rack gear 76, the member 73 will be locked from rearward movement by the pawl 80, the friction connection between the members 73, 74 permitting a slipping movement between them. The two springs 53 are wound in opposite directions and the pawls 80 for the two ratchet members are oppositely disposed, as seen in Fig. 8, so that the movement of the rack bar 76 in one direction will wind up one spring, the friction connection for the other spring yielding or giving at this time, while the movement of the rack bar in the opposite direction will wind said other spring, the friction connection for the first-named spring yielding or giving during this operation. It will thus be seen that

the opening and closing movement of the oven door 9 is utilized to keep the springs 53 wound.

It will be understood, of course, that I will use suitable pilot burners in the oven for lighting the main burners as the valves 39 and 390 are opened, but I have not shown such pilot burners herein as they do not form any part of my present invention.

I will preferably make the oven bottom 10 adjustable vertically. One way of accomplishing this is shown in Fig. 15 wherein the sides of the oven are provided with teeth 92 and the oven bottom 10 is provided with plates 93, 94 at opposite edges which engage and rest on the teeth. The plate 94 is adjustable and is held in adjusted position by a screw 95 operating through a slot 96 in the plate 94. When the screw 95 is loosened and the plate 94 moved backwardly the oven bottom can be adjusted to any desired height, after which it may be locked in its adjusted position by tightening up the screw 95.

While I have herein illustrated the invention as it might be embodied in an oven adapted to use gas as fuel, yet I desire to state that the invention is equally applicable to ovens heated by other fuel than gas, such as above stated many features of the invention are also applicable to an oven which is heated by electricity. Hence I do not wish to be limited to any particular character of heating element. Furthermore, although I have illustrated herein a selected embodiment of my invention, yet I do not wish to be limited to the constructional features shown.

I claim:

1. In an oven, the combination with an oven chamber, of a plurality of burners for heating said chamber, a fuel supply valve for each burner, automatically-operative valve-actuating devices normally held inoperative, and automatic means to release said devices successively when the temperature in the chamber increases beyond a predetermined point whereby the valves will be closed in succession.

2. In an oven, the combination with an oven chamber, of a plurality of burners for heating said chamber, a fuel supply valve for each burner, automatically-operative valve-actuating means for successively closing and opening each valve, and thermostatic means to control the operation of said valve-actuating means to effect the closing of the valves successively as the temperature increases and the opening of the valves successively as the temperature decreases.

3. In an oven, the combination with an oven chamber, of a plurality of burners for heating the oven, a fuel supply valve for

each burner, a motor device for closing each valve, and thermostatic means to render said devices operative to close one valve when the temperature in the oven reaches a predetermined point and to close another valve when the temperature reaches a higher point.

4. In an oven, the combination with an oven chamber, of a plurality of burners for heating the oven, a fuel supply valve for each burner, a motor device for operating each valve, and thermostatic means to render said devices operative successively to close first one valve and then another when the temperature in the oven increases beyond a predetermined point and to open first one valve and then another when the temperature decreases.

5. In an oven, the combination with an oven chamber, of a plurality of burners for heating said chamber, the latter having an inlet opening through which air is supplied to support combustion, a fuel supply valve for each burner, automatic means to close the valves successively as the temperature in the chamber rises above a predetermined amount and means to close said opening when all of the valves are closed.

6. In an oven, the combination with an oven chamber, of a plurality of burners therefor, said chamber having air-inlet openings through which air is supplied to support combustion, a fuel supply valve for each burner, automatic means to close the valves successively as the temperature in said chamber rises above a predetermined amount and to open said valves successively when the temperature decreases and means to close said air-inlet openings when all of the valves are closed and to open said openings when one of the valves is open.

7. In an oven, the combination with an oven chamber having a door, of a burner for heating the oven, a fuel supply valve for said burner, automatically-operative valve-actuating means to close said valve when the temperature rises above a predetermined point, and to open said valve when the temperature falls below said point, and means operated by the opening and closing movement of the door to store up energy in said automatically-operative means.

8. In an oven, the combination with an oven chamber having a door, of a burner for heating said chamber, a fuel supply valve for said burner, a thermostatically-controlled valve-actuating spring for operating the valve, and means operated by the opening and closing movement of the door to store up energy in said spring.

9. In an oven, the combination with an oven chamber having a door, two burners for heating the oven, a fuel supply valve for each burner, a thermostatically-controlled spring for actuating each valve and means

operated by the opening movement of the door to store up energy in one spring and by the closing movement of the door to store up energy in the other spring.

10. In an oven, the combination with an oven chamber, of two valves for heating said oven, a valve-actuating spring for each valve, thermostatic means to control the operation of the valves, a spring-winding element actuated by the opening and closing movement of the oven door, and means whereby said element winds one spring when the door is open and the other spring when the door is closed.

11. In an oven the combination with an oven chamber having a door, of a burner element, two fuel supply valves to supply fuel thereto, a spring for actuating each valve, thermostatic means to control the operation of each valve, a rack bar connected to the door to be reciprocated as the door is opened and closed, gears meshing with the rack bar and connections between said gears and said springs whereby one gear operates to wind up one spring when the door is opened and the other gear operates to wind up the other spring when the door is closed.

12. In an oven, the combination with an oven chamber, of a burner element for heating the same, two fuel supply valves, each having a rotary valve member capable of rotation continuously in one direction and which opens and closes the valves successively as it rotates, means tending normally to rotate each valve member, and a thermostatically-controlled member controlling the operation of both valves.

13. In an oven, the combination with an oven chamber, of a burner element for heating said chamber, two valves each having a rotary valve member capable of rotation continuously in one direction and which opens and closes the valves successively as it rotates, means tending to rotate each valve member, and a thermostatically-controlled valve-controlling member normally restraining the operation of both valves but adapted to permit their operation successively as it is moved.

14. In an oven, the combination with an oven chamber having a door, a burner element for heating said chamber, two fuel supply valves, each having a rotary valve member capable of rotation continuously in one direction and which opens and closes the valve successively as it rotates, a spring tending to rotate each valve member, a thermostatic device to control the operation of the valves and means operated by the opening and closing movement of the door to wind said springs.

15. In an oven the combination with an oven chamber having a door, of a burner, a fuel supply valve having a rotary valve member capable of rotation continuously in

one direction and which opens and closes the valve successively as it rotates, a spring tending to rotate said valve member, a thermostatic device to control the operation of the valve and means operated by the opening and closing movement of the door to wind up said spring.

16. In an oven, the combination with an oven chamber, of a burner therefor, a fuel supply valve, automatically-operative means to operate the valve, a thermostatic rod in said chamber anchored at one end, a lever connected to the other end of said rod, a controlling member connected to said lever and controlling the operation of the valve-actuating means and a spring connected to said member.

17. In an oven, the combination with an oven chamber, of a burner therefor, a fuel supply valve, automatically-operative means to operate the valve, a thermostatic rod extending through the oven, an anchoring nut screwed to said rod by which the latter may be adjusted, a lever connected to the rod, a controlling member connected to the lever and controlling the operation of the valve-actuating means and a spring acting on said member.

18. In an oven, the combination with an oven chamber, of a thermostatic rod extending therethrough, an anchoring nut screw threaded to said rod, a fuel supply valve, a valve-controlling member connected to said rod, a spring acting on said member, said anchoring nut having gear teeth and an indicating member geared to said nut and by which the adjustment thereof may be indicated.

19. In an oven, the combination with an oven chamber, of a burner therefor, a fuel supply valve comprising a stationary member having two chambers constituting inlet and outlet chambers respectively, a rotary valve member having ports, thermostatically controlled means to effect an intermittent rotary movement of said valve member, the ports therein operating to establish and interrupt communication between said chambers successively during such intermittent movement.

20. In an oven, the combination with an oven chamber, of a burner therefor, a fuel supply valve comprising a stationary member provided with an inlet and an outlet chamber respectively and a ported valve face, a rotary valve member having a chamber journaled in the stationary member and provided with a ported valve face which engages that of the stationary member, yielding means to hold the valve faces in contact, and thermostatically-controlled means to give the valve member an intermittent rotary movement.

21. In an oven, the combination with an oven chamber, of a plurality of heating

elements therefor, a controller for each heating element, an automatically-operative device tending constantly to actuate each controller, and a thermostatically-controlled member normally locking said automatically-operative device from operation but adapted in one position to release one of said devices and in another position to release the other of said devices.

22. In an oven, the combination with an oven chamber, of a heating element to heat the latter, a device to control the heating element and render the same operative and inoperative alternately, a spring to actuate said device, a toothed member associated with said device, the successive teeth of which are out of line with each other, a notched controlling bar engaging said toothed member, and a thermostatic member connected to said bar for actuating the same, whereby the heating element is rendered inoperative or operative as the temperature in the oven chamber rises and falls.

23. In an oven, the combination with an oven chamber, of a heating element therefor, a spring-actuated device to render said heating element operative or inoperative, a member to control the operation of said spring-actuated device, a thermostatic rod in said chamber anchored at one end, connections between said rod and said member, and a spring associated with said connections to take up lost motion.

24. In an oven, the combination with an oven chamber, of a plurality of burners for heating said chamber, said chamber having an air inlet opening through which air is supplied to support combustion, a fuel supply valve for each burner, thermostatically-controlled means to close the valve successively as the temperature in said chamber rises above the predetermined point and means to close the air inlet opening progressively as the valves are closed.

25. In an oven, the combination with an oven chamber, of a plurality of burners for heating said chamber, said chamber having an air inlet opening through which air is supplied to support combustion, a fuel supply valve for each burner, automatic means to close the valve successively as the temperature in said chamber rises above the predetermined point and means controlled by the valve-actuating mechanism to close the air inlet opening progressively as the valves are closed.

26. In an oven the combination with an oven chamber, of two burners therefor, said chamber having an air inlet opening, a fuel supply valve for each burner, thermostatically-controlled means to close the valves successively as the temperature in said chamber rises above a predetermined amount and means associated with the valve-actuating means to partially close the air inlet opening.

when the first valve is closed and to completely close said opening when the other valve is closed.

27. In an oven the combination with an oven chamber, of a plurality of burners therefor, said chamber having an air inlet opening, a fuel supply valve for each burner, automatic means to close the valve successively as the temperature in said chamber rises above a predetermined amount and to open said valves successively when the temperature decreases, and means to close the air inlet opening progressively as the valves are closed successively and to open said opening progressively as the valves are opened successively.

28. In an oven the combination with an oven chamber, of two burners therefor, said chamber having an air inlet opening, a fuel supply valve for each burner, automatic means to close the valves successively as the temperature in said chamber rises above a predetermined amount and means associated with the valve-actuating means to partially close the air inlet opening when the first valve is closed and to completely close said opening when the other valve is closed, and to partially open said air inlet opening when

the first valve is opened and completely open said opening when the second valve is opened.

29. In an oven, the combination with an oven chamber, of a series of burners for heating said chamber, a series of fuel supply valves for said burners, a motor device for operating each valve, and thermostatic means for controlling and causing said motor devices to operate successively as the temperature in the oven varies.

30. In an oven, the combination with an oven chamber, of a heating element therefor, a controller for said heating element, automatically-operative means tending to actuate the controller, a bar normally locking said means from operation but adapted in one position to release said means, and a thermostatic device to control the position of said bar.

In testimony whereof, I have signed my name to this specification, in the presence of two subscribing witnesses.

ARTHUR M. BURNHAM.
